GRAIN SEPARATING DRUM

Leonard Johnson, Minneapolis, Minn., assignor
to Hart-Carter Company, Peoria, Ill., a corpora-
tion of Delaware

Application February 11, 1936, Serial No. 63,350

1 Claim. (Cl. 209—95)

My present invention relates particularly to grain separating drums and is in the nature of an improvement on or modification of the "separating drum" disclosed and claimed in an application filed by myself, Leonard Johnson, and Martin A. Rieman, of even date herewith.

The invention is in the form of a valley and ridge forming corrugations that are extended longitudinally in the drum; in fact, the corrugations of this application, except for certain features hereinafter noted, are preferably the same as those of the said joint application. The valleys and ridges of this application, as in the joint application, are obviously extended substantially from end to end of the operating surface of the drum. The valleys of the present application, as in the joint application, are of such narrow width that the separation of different kinds of grain or material is in accordance with the thickness of the grain kernels. In this specification also the term "thickness" is used to indicate, or to mean, the narrowest or smallest dimension of the grain kernel.

In practice I have found that with the continuous or very long valleys straw and light, long but narrow material will sometimes get into the valleys and be carried from the body of the stock with the narrow or thin grain. This I have found can be avoided by placing bridge ribs or bulges transversely in the bottoms of the valleys, as will hereinafter more fully appear.

Referring to the drawing wherein like characters indicate like parts throughout the several views:

Fig. 1 is an elevation of the improved drum some parts being broken away and some parts being sectioned.

Fig. 2 is a fragmentary plan view looking at the inner surface of the drum.

Fig. 3 is a section taken on the line 3—3 of Fig. 2.

Fig. 4 is a longitudinal section taken on line 4—4 of Fig. 3; and

Fig. 5 is a transverse section taken on the line 5—5 of Fig. 4.

The drum illustrated comprises a sheet metal shell 6, and open heads 7 and 7a. The drum, as is obvious, may be supported and operated in various different ways but may be assumed to be a drum of a grain separating machine of the type disclosed and claimed in the Ingraham Patent #2,015,400, dated Sept. 24, 1935. The drum of that machine is provided with indentations or pockets which reject long grain such as oats, for example, but pick up wheat and carry the same

to a high elevation where the latter will be discharged from the pockets into a receiving trough thereby accomplishing the separation of relatively short from relatively long grain, but irrespective of the thickness or smallest dimension of the grains. In a general way, it may be assumed that the improved drum may be used as a substitute for the drum of the Ingraham patent, but in which case with the improved compound valley and ridge forming corrugations the different type of separation above indicated, or hereinafter more fully described, will take place.

As best shown in Fig. 3, the drum is corrugated to form the valleys and intervening ridges. The valleys are deep and narrow and their walls diverge slightly so that the grain received therein will be gravity held but not frictionally held. The ridges 9 formed between the valleys 8 are also of novel design, and they extend from lines marked "a" to lines marked "b". The valleys proper terminate on the lines "a" and the ridges begin on these lines and converge to lines "b" that form their salient angles.

The width of the valleys 8 will vary in different machines according to the kind of operations to be accomplished. If, for example, the function to be performed is the separation of thin or shrivelled or undeveloped oats from relatively thick and well developed oats then the valleys should be just wide enough to receive the relatively thin grain when the kernels are extended longitudinally in the valleys, but not wide enough to receive the relatively thick oats.

When the mixed or commingled grains of various thickness are fed into the drum, and the drum is rotated, the grain will be carried upward on the rising side of the drum and will roll backward over the ridges under the action of gravity. Each of the units of grain illustrated, which I have assumed to include oats, becomes parallel to the valleys. The relatively thin oats will fall into the valleys and will be carried upward to a point high enough for the discharge into the receiving trough, not shown, but which, as stated, would be provided in the machine of the type indicated, while the relatively thick oats or other materials that are thicker than the valleys are wide will roll back and finally be discharged from one end of the drum.

It is important to note that the ridges 9 slant back from their salient edges "b" toward the two adjacent valleys so that the oats or other grain rolling down the incline will tend to become parallel to the valleys. When the grain, assumed to be oats, gets parallel to the valleys the shrivelled,

poorly developed and thin oats will drop into the valleys while the thick oats will not enter the valleys but will be rolled back toward the bottom of the drum. The ridges formed, as described, 5 carry the grain in such a way as to prevent the grain caught in the valleys from being swept out of the valleys.

The thin or narrow grain, regardless of length, lodged in the valleys at the lower portion of the 10 drum will, under the action of gravity, be held in the valleys until the valleys have reached an elevation at which gravity, instead of holding the grain in the valleys, will dislodge the grain and cause the same to be "poured out" of the 15 valleys and into the trough or catch receptacle within the drum. Under rotation of the drum, and especially when the drum is rotated at considerable speed, centrifugal force will also tend to hold the grain in the valleys; and in fact, the 20 grain will be held in the valleys until the latter have reached such elevation and their walls changed their angular position in respect to vertical, to such an extent that gravity will overcome centrifugal force and the sliding friction of 25 the grain and cause the same to slide or roll out of the valleys into the trough or receptacle. The diverging walls of the valleys, however, prevent the grain from being wedged and frictionally held in the valleys, and hence, the discharge 30 thereof will be as above stated.

As has been stated, the valleys 8 actually terminate on the lines "a". It will be understood that the width of the valleys is determined by the distance between the lines "a—a", and that 35 the reversely beveled, or inclined surfaces of the ridges are beyond said lines "a".

With the valleys and ridges extended from, or approximately from, end to end of the operating 40 surface of the drum all of that drum surface is rendered effective for accomplishing the operation by the thickness above described. Obviously, length of the grain or material does not enter into the operation inasmuch as the thin long grain kernel will get into a valley as readily as 45 a shorter one of the same thickness. This type

of operation is highly important for the separation of not only thin and thick oats but thin and thick barley and thin and thick wheat or for the operation of different commingled grains where- 5 in it is desired to take out of the mixture relatively thin grain irrespective of length.

As a feature of this invention, the valleys 8 at spaced intervals are formed with transverse bulges or bridge forming ribs 10 that extend to the tops of the valleys but advisably not to the salient angles "b" of the ridges 9. These bulges or bridge-forming ribs 10 are preferably formed by being displaced from the sheet metal of the drum. Said ribs are so spaced that they will engage straws or the like and prevent the same 15 from becoming lodged in the valleys and carried with the narrow or thin grain out of the body of the stock. I have found that the best results will be obtained by extending the ribs only to the tops of the valleys proper so that they may have 20 the diverging surfaces of the ridges continuous or approximately so. In actual practice the efficiency of this improved separating drum has been demonstrated.

What I claim is:

A grain separating drum having longitudinally extended, relatively narrow but flaring substantially symmetrical valleys adapted to receive grains transversely of their length, relatively wide and shallow intervening ridge-like portions 30 adjoining the upper edges of the valley walls at angles thereto and providing oppositely inclined relatively long and flat rolling surfaces which are substantially symmetrical and on which grains are caused to roll about their longitudinal axes 35 towards and into said valleys upon rotation of the drum, and a straw engaging and supporting rib extending transversely between the walls of the valleys adjacent their upper edges and merging with the walls of said ridge-like portions, 40 whereby grains may enter said valleys transversely of their length while straw and like bodies are deflected from the valleys and caused to roll over the surfaces of said ridges.

LEONARD JOHNSON. 45
